UNITED STATES PATENT OFFICE.

ARTHUR C. DAVIDSON, OF CHICAGO, ILLINOIS, ASSIGNOR, BY MESNE ASSIGNMENTS, TO WAUGH EQUIPMENT COMPANY, OF CHICAGO, ILLINOIS, A CORPORATION OF MAINE.

DRAFT-GEAR CASING.

Application filed November 27, 1922. Serial No. 603,420.

To all whom it may concern:

Be it known that I, ARTHUR C. DAVIDSON, a citizen of the United States, and a resident of the city of Chicago, in the county of Cook and State of Illinois, have invented certain new and useful Improvements in a Draft-Gear Casing; and I do hereby declare that the following is a full, clear, and exact description of the same, reference being had 10 to the accompanying drawings, and to the numerals of reference marked thereon, which form a part of this specification.

In the construction of draft gears, for railway car constructions, a cushioning mechanism is provided to which the drawbar is connected for the purpose of absorbing the pulling and pushing strains. The arrangement for accommodating the draft gear is substantially the same in all cars. 15 The draft sills are arranged an established distance apart and are connected at the bottom by a draft gear carry iron upon which the drawbar yoke carrying the cushioning elements is adapted to slide. In the 20 type of constructions using friction plates for the cushioning elements considerable trouble has been caused due to the fact that the draft sills are not spaced the proper distance apart or may be bent or otherwise 25 distorted so that there is play between the ends of the friction plates and the draft sills or on the side plates when used. With 30 this condition it has been found that the friction plates together with the separators 35 are permitted to have considerable transverse movement with respect to one another, thereby causing the ends of the friction plates to continually pound or contact 40 against the inner faces of the side plates and the draft sills. This action of the friction plates eventually causes the side plates and the draft sills to be worn through, requiring replacement thereof.

To obviate the above mentioned defects, 45 this invention relates to a friction plate housing or casing adapted to be engaged within the drawbar yoke with the ends of said casing slidably engaged between the draft sills. This arrangement prevents the 50 ends of the friction plates from engaging and wearing holes in the draft sills.

It is an object of this invention to provide a casing for the friction elements of a draft gear to prevent said friction elements from

acting against the draft sills of a car to 55 wear the same out.

It is also an object of the invention to provide a housing for use in a draft gear, said housing replacing the usual side plates and adapted to separate the friction elements from the car draft sills to prevent 60 wearing out of said draft sills.

It is a further object of the invention to provide an improved draft gear adapted to be readily mounted in the standard space 65 provided therefor in a car without requiring any change in the standard structure.

It is furthermore an object of this invention to provide an improved type of draft gear adapted to be readily mounted in a 70 car and provided with means for protecting the draft sills of the car against the wearing action of the friction elements of the draft gear.

It is an important object of this invention 75 to provide an improved draft gear construction adapted to be installed in a standard railway car construction and retained in place by carry irons adapted to be secured to the draft sills of the car.

Other and further important objects of this invention will be apparent from the disclosures in the specification and the accompanying drawings.

The invention (in a preferred form) is 85 illustrated in the drawings and hereinafter more fully described.

On the drawings:

Figure 1 is a fragmentary sectional top plan view of the draft sills of a railway car 90 construction accommodating an improved draft gear partly shown in section.

Figure 2 is a longitudinal sectional view taken on line 2—2 of Figure 1.

Figure 3 is a fragmentary top plan view 95 of the draft sills and the draft gear with parts of a sill plate broken away.

Figure 4 is a side elevation of the draft gear shown connected to a drawbar.

Figure 5 is an enlarged transverse section taken on line 5—5 of Figure 2.

Figure 6 is an enlarged transverse section taken on line 6—6 of Figure 2.

As shown on the drawings:

The reference numeral 1 indicates a pair of railway car draft sills of channel iron construction which are mounted longitudinally on the car. A plate 2 connects the 100 105

upper flanges of the draft sills. Secured to the lower flanges 3 of the draft sills 1 by means of bolts 4, is a carry iron 5 comprising a broad plate or bar, the ends of which are bent to form flanges 6 which project upwardly beyond the lower sill flanges 3. The carry iron 5 is located below the point where the shock absorbing device of the draft gear is to be positioned.

Secured to the inner face of each draft sill 1, are front and rear blocks or castings 7 and 8, respectively, which are riveted to the sills as at 9 and positioned at the front and rear respectively of the carry plate 5 to afford a space into which the shock absorbing device of the draft gear is adapted to fit. The castings 7 and 8 are provided with integral inwardly directed flanges 10 and 11 respectively, which serve as stops or abutments for the shock absorbing device.

The shock absorbing device comprises a series of groups of similar friction plates 12 with the plates in each group placed face to face and adapted to be collectively bowed or bent by either thrusting or pulling strains applied to a coupler or drawbar 13. The two middle groups of friction plates 12 are separated by a double convex spacer block 14. The outer groups of friction plates are separated by double concave separator blocks 15. Positioned against the outer friction plate 12 of each end group of plates is the convex inner face plate 16 of a follower block 17. Each follower block 17 is provided with upper and lower lugs or projections 18 and 19 respectively.

The groups of friction plates 12, the separators 14 and 15, and the follower blocks 17 are all disposed within a casing or housing 20 open at both ends and having recesses 21 at both ends of the upper and lower plates thereof. Openings 22 are provided in the side walls of the casing 20. Integrally formed on the top and bottom of the casing 20 are guide shoes 23 and 24 respectively. The lower shoe 24 is adapted to rest on the lower bar of a yoke strap 25 which is engaged around the casing 20 and the shock absorbing mechanisms contained within said casing. The ends of the yoke strap 25 are rigidly secured by bolts or rivets to a head 26 integrally formed on the drawbar 13. The yoke 25 is positioned to ride on the carry iron 5 as illustrated in Figure 2. The follower blocks 17 are adapted to abut against the front and rear stop flanges 10 and 11 of the castings 7 and 8. The front follower block 17 is also in contact with the drawbar head 26 while the rear follower block 17 is seated against the bight of the yoke 25.

As clearly illustrated in the drawings, the friction plates 12, together with the follower blocks 17 and the separators 14 and 15 are all positioned within the casing 20. The

casing 20 is disposed within the yoke 25 and between the stop flanges 10 and 11. This arrangement prevents any wearing action by the shock absorbing members on the draft sills 1. Inasmuch as the casing 20 forms a part of the draft gear mechanism, the friction plates 12 may be made to fit transversely therein so that there will be no substantial space for movement between the ends of the friction plates and the side walls of the casing 20. It will thus be noted that the improved draft gear construction of this invention is so designed that the wear on the draft sills is eliminated due to the use of the draft casing 20 which contains the shock absorbing elements.

In view of the fact that the draft sills of a railway car are usually covered by flooring, it is desirable that the draft gear be adapted to be mounted in position from below and accessible to permit of replacement and repairs. In the improved construction of this invention the drawbar 13 before being mounted in place has the yoke 25 rigidly secured thereto. The casing 20 is now placed within the yoke and pushed rearwardly as far as it can go with the bight of the yoke 25 engaged in the recesses 21 at the rear end of the casing. The front follower 17 is next inserted in the forward part of the yoke between the drawbar head 26 and the front end of the casing 20. The casing 20 is now pushed forward as far as it will go with the front follower 17 engaged in the front recesses 21 of the casing 20. The friction plates 12 and the separators 14 and 15 are next inserted through the rear open end of the casing 20 through the space between the rear end of the casing 20 and the bight of the yoke 25. The rear follower 17 is pushed into place between the bight of the yoke 25 and the last group of plates, as illustrated in Figure 4, and the casing 20 is then pushed back toward the bight of the yoke to engage said rear follower. The draft gear is thus easily assembled before mounting upon the railway car.

The assembled draft gear is now jacked up and raised in place between the car draft sills 1 with the casing 20 positioned between the stop flanges 10 and 11 as illustrated in Figure 3. A retaining channel bar 27 is next secured to the car frame by any suitable means to support the drawbar 13. The yoke 25 is supported upon the transverse carry iron 5 which is secured to the lower flanges 3 of the draft sills 1, thereby supporting the rear end of the draft gear in place. The draft gear is thus permitted to be mounted in place as an assembled unit without requiring any changes or alterations of the standard parts of the car structure.

I am aware that numerous details of con-

struction may be varied through a wide range without departing from the principles of this invention, and I therefore do not purpose limiting the patent granted otherwise than necessitated by the prior art.

I claim as my invention:

In a device of the class described, the combination with a pair of draft sills, a draw bar therebetween, means secured to the draft sills to support the draw bar in position, a yoke secured to the draw bar, a carry iron connecting said draft sills to support said

yoke, a unitary stationary casing in said yoke having portions cut out of the ends of the top and bottom walls thereof, guide shoes integrally formed longitudinally on the bottom and top of said casing and terminating at the cut out portions of said casing, and shock absorbing elements in said casing between the draw bar and the bight of said yoke.

In testimony whereof I have hereunto subscribed my name.

ARTHUR C. DAVIDSON.
